UNITED STATES PATENT OFFICE.

JOHN M. PRICE, OF KINGS BRIDGE, NEW YORK.

SKELP-ROLLING MACHINE.

SPECIFICATION forming part of Letters Patent No. 373,481, dated November 22, 1887.

Application filed August 10, 1887. Serial No. 246,560. (No model.)

To all whom it may concern:

Be it known that I, JOHN M. PRICE, of Kings Bridge, in the county and State of New York, have invented certain new and useful 5 Improvements in Mills for Rolling Skelps, of which the following is a specification.

The object of this invention is to furnish an improved apparatus or mill for rolling iron or steel skelps to be used for the manufacture of 10 wrought-iron and steel tubes, also for rolling out iron or steel nail-plates, the invention being designed with a view to expedite the rolling out of the skelps or plates, reduce the 15 number of hands required for attending to the mill, and increase the output of the same.

Heretofore in rolling out iron or steel skelps of this class a train of rolls was used which consisted of a three-high roughing set, a three-high finishing set, and a two-high planishing 20 set of rolls, said three sets of rolls being arranged in line and provided with stationary platforms at one side or in front of the rolls, said platforms being provided with driven feed-rollers to assist the roughers or finishers

25 in returning the billet to the rolls. At the other side or rear of the rolls the billet is handled with tongs, raised by means of hooks, and guided back into the several passes of the rolls, said tongs and hooks being also used for 30 transferring the billet from one set of rolls to the other, so as to require, therefore, in mills making skelps from ten to fifteen inches wide about thirteen or fourteen men for rolling out and delivering the skelps to the shears. By

35 my improved rolling-mill the skelps can be rolled out in any suitable width and delivered to the trimming-shears by five men and boys, as a number of the operations referred to are accomplished by means of specially-designed 40 appliances.

The invention consists of a rolling-mill for making skelps and nail-plates, which comprises three sets of rolls arranged in line with each other, a set of roughing-rolls, a set of finishing-rolls, and a set of planishing-rolls, a stationary feed-table arranged at the front of the first set of rolls, a rising and falling feed-table at the opposite side of the same, a stationary feed-table at the front of the second 45 set of rolls, a traversing carriage having a rising and falling platform hinged to said carriage and moving along the said second set of

rolls, and feed devices for the third set of rolls. The rising and falling feed-table at the rear of the roughing-rolls is provided with shifting devices for laterally moving the billet into line with the upper passes of said rolls and into contact with continuously-rotating feed-rollers. The shifting devices of the rising and falling feed-table also serve to transfer the billet to pivoted arms of the traversing carriage by which the billet is transmitted to the hinged platform of the same, said platform being provided with oscillating dogs for stopping the billet, which dogs are operated by a fixed cam-stop at the proper time and moved out of the way when the skelp is to be transmitted from said platform by oscillating dogs of the traversing carriage over an inclined conducting-plate into line with the planishing-rolls, and 60 by suitable feed devices to the same and the trimming-shears.

The invention consists, further, of certain details of construction and combinations of parts, as will fully appear hereinafter, and finally be 65 pointed out in the claims.

In the accompanying drawings, Figure 1 represents a plan of my improved rolling-mill for making skelps or nail-plates. Fig. 2 is a side elevation of the same. Figs. 3, 4, and 5 70 are vertical longitudinal sections, respectively on lines *x x* and *y y*, Fig. 1. Fig. 6 is a rear elevation of the apparatus; Fig. 7, a vertical transverse section on line *c c*, Fig. 1. Fig. 8 is a plan, drawn on a larger scale, of the rising 75 and falling tables for transmitting the billet to the passes of the roughing and finishing rolls. Fig. 9 is a vertical transverse section of the same on line *k k*, Fig. 8; and Figs. 10 and 11 are vertical longitudinal sections on line *l l*, 80 Fig. 8, showing the dogs of the feed-table of the finishing-rolls in different positions.

Similar letters of reference indicate corresponding parts.

In the drawings, A represents a set of three-high roughing-rolls, B a set of three-high finishing-rolls, and C a set of two-high planishing-rolls, which are arranged in line with each other and coupled together, so as to receive motion from the same shaft, as customary in 85 rolling-mills. At one side or front of the first set of roughing-rolls, A, is arranged an inclined stationary table, A', which is provided with a number of rollers, *a*, that are rotated by in- 90

termeshing gearing, to which motion is imparted by a belt-and-pulley transmission from a suitable power-shaft. The driving-rollers of the table A' are connected with a reversing-5 gear, which enables the operator to prevent the billet from entering the rolls A if this should not be desired. The billet is placed on the inclined table A', and fed by the rollers a between a fixed guide rail or pins, a', to the 10 first pass of the roughing-rolls, and forced through the same to the opposite side or rear of the roughing-rolls A onto a vertically rising and falling feed-table, A², which is provided with rollers a², for receiving the billet, 15 and with longitudinal rails a⁴, for guiding and shifting the same on the feed-table A². The frame of the feed-table A² is provided with upright posts a⁵, having racks a⁶, that mesh with gear-wheels a⁷, which are turned in opposite 20 direction to each other by a crank and connecting rod of an actuating steam-engine, as shown in Figs. 2 and 3.

The feed-table A² is raised and lowered at the proper time, so as to receive the blank from 25 the lower passes and feed it to the upper passes of the roughing set of rolls. The rollers a² at the end of the table next to the rolls A serve, in connection with the continuously-rotating feed-rollers a⁸ a⁹, the shaft of which is supported in bracket-bearings fastened to the standards of the rolls A, to move the billet 30 into the upper passes of the roughing-rolls A. The guide-rails a⁴ of the feed-table A² are connected to the rails of a shifting-frame, a¹⁰, which 35 is guided in ways of the frame of the feed-table A² and provided with a friction-roller, a¹¹, at the outer end, which friction-roller is engaged by an inclined way, a¹², so as to reciprocate the shifting-frame a¹⁰ by the combined action of the 40 rising and falling motion of the feed-table A² and the inclined way a¹², and cause thereby the billet to be laterally shifted on the feed-table A² into line with the upper passes of the roughing-rolls. The inclined guideway a¹² is supported 45 on an upright standard, a¹³, and adapted to be adjusted to different degrees of inclination on the same by a set-screw, a¹⁴, passing through an arc-shaped slot, a¹⁵, of the standard a¹³, as shown in Figs. 6 and 7. By adjusting 50 the inclined guideway a¹² to a greater or smaller angle of inclination to its supporting-standard a¹³, the extent of the shifting motion may be regulated according to the width of the skelps or nail-plates to be rolled from the billet. The 55 rollers a² and feed-roller a⁸ feed the billet to the second pass and back to the inclined table A', the rollers of which again feed the billet to the third pass at the lower part of the rolls A and through the rolls to the rising and falling 60 feed-table A². The billet is next moved by the shifting-frame a¹⁰ laterally on the feed-table A² into line with the fourth pass of the roughing-rolls A and into contact with the second continuously-rotating feed-roller, a⁹, which latter 65 moves the billet to the fourth pass and through the same to the inclined table A'. The feed-rollers of the table A' move the billet to the

fifth pass at the lower part of the rolls A and back to the feed table A² and onto pivot-arms d d of a traversing carriage, D, said arms entering into recesses d' d' of the frame of the feed-table A², as shown in Figs. 8 and 9. The arms d d are guided and steadied in fixed recessed blocks d² d², located alongside the rising and falling feed-table A². The billet is transferred to the pivot-arms d d while the feed-table is in its lowermost position, so that when the feed-table is raised the arms are raised simultaneously therewith into inclined position, as shown in Fig. 6, and cause the billet 80 to slide by gravity over the inclined arms d d onto a platform, D', hinged at one end to a traversing carriage, D. (Shown in Figs. 4, 8, and 9.)

The platform D' is provided with pivoted dogs 85 d³ d³, that are connected at their lower ends by a pivot-rod, d⁴, as shown in Fig. 10, one of said dogs passing along a fixed inclined cam, d⁵, when the carriage D is moved toward the rising and falling feed-table A², said cam causing 90 the dogs to oscillate on their pivots and project by their upper ends above the level of the platform D', as shown in Fig. 11, so as to prevent the billet from passing beyond the same. The platform D' is provided at the end next to 95 the rolls B with a roller, d⁶, that turns in bearings of the same and brings the billet in contact with a continuously-rotating feed-roller, d⁷, the shaft d⁸ of which is supported in bracket-bearings of the standards of the second set 100 of rolls, B, when that end of the platform is lifted, so as to move the billet to the upper passes of the same. When the billet has been transferred by the pivot-arms d d onto the hinged platform D', the traversing carriage D 105 is moved on its rails e e alongside of the second set of rolls, B. The platform D' is then raised by a U-shaped lever-frame, d⁹, which is operated by a lever, d¹⁰, that is located side-wise of the planishing-rolls C, and applied to the outermost end of a shaft, d¹¹, turning in 110 suitable bearings, as shown in Fig. 4, so that the billet is brought in contact with the feed-roller d⁷, and is fed thereby to the sixth pass of the rolls B and through the same onto a 115 stationary inclined table, B', at the front of the finishing-rolls, which table, like the table A', is provided with tapering guide-pins d¹² for the billet. The traversing motion of the carriage D parallel to the rolls B on its rails e e is accomplished by means of pinions f f, that engage racks f' f' of the carriage, said pinions being applied to a shaft, f², which receives rotary motion in one or the opposite direction by a bevel-wheel, f³, at its end, bevel-wheels f⁴ f⁴ on a power-shaft, f⁶, and a clutch mechanism, f⁵, between said bevel-wheels, the shifting of the clutch mechanism into gear with one or the other bevel-wheel f⁴ imparting a traversing motion to the carriage in one or the opposite direction along the finishing-rolls, so as 120 to bring the hinged platform D and the billet transferred to the same at the proper time into line with the passes of the same.

The stationary inclined table B' is provided with fixed standards g , g , to which is fulcrumed a balanced frame, g' , that carries a roller, g^2 , at its rear end and a balancing-weight, g^3 , for the same at a forward-extending arm. The roller-frame g' is raised or lowered by a lever, g^4 , operated by one of the attendants. A roller, g^5 , at the rear end of the table B' receives continuous rotary motion by a suitable belt-and-pulley transmission, and serves, in connection with the roller g^2 of the frame g , when the same is lowered, to move the billet to the lower passes of the finishing-rolls B—namely, the seventh, ninth, and eleventh of the whole number of passes—whenever the same is fed by the lifting motion of the platform D' and the action of the rollers d^6 , d^7 to the upper passes, 6, 8, and 10, of the finishing-rolls, and through the same to the table B'. When the billet has passed the eleventh pass, it is rolled out nearly to the full length of the skelp to be produced, and is conveyed by the platform D' and the traversing carriage D to an inclined plate, E, by means of oscillating dogs h , h , that are applied to a transverse shaft, h' , of the carriage D. The shaft h' turns in suitable bearings of the carriage D, and has a crank-arm, h^8 , at its outer end, that comes in contact with a fixed stop, h^9 , as shown in Fig. 7, so as to oscillate the dogs at the proper moment and cause the skelp to be transferred onto the inclined plate, along which it slides by gravity into a depressed guideway, E', at the rear of the third set or planishing-rolls, C. The carriage D is then returned in opposite direction by the attendant stationed at the clutch of its driving-gear, the dogs h , h being then returned into their normal position, as shown in dotted lines in Fig. 6, by means of weights h^4 , applied to fixed arms of the shaft h' .

A continuously-rotating feed-roller, i , is arranged in the guideway leading to the planishing-rolls C, and serves, in connection with a balanced U-shaped frame, i' , having a roller, i^2 , at its outer end, and a lever, i^3 , to move the skelp forward below the lower roll of the third set, C, to the other or front side of the same, where it passes along an inclined or curved part, E², of the guideway E', and is taken hold of by tongs operated by an attendant and bent toward the rolls C, so as to be inserted between the same and moved by them through the twelfth and last pass of the mill, as shown in dotted lines in Fig. 5. From the rolls C the skelp is delivered onto a stationary table, F, and transferred from the same by a continuously-rotating roller, m , and a U-shaped balanced frame, m' , having a roller, m^2 , and lever m^3 , connected by a rod, m^4 , to the lever i^3 , in the same manner as it has before been driven under the rolls to the trimming shears, where the skelp is cut to the proper length.

Operation: The operation of the rolling-mill has been described to some extent in connection with the different parts composing the same, so that it is only necessary to briefly re-

capitulate the successive movements of the different parts and the successive feeding of the billet in one heat through the five passes of the roughing-rolls, the six passes of the finishing-rolls, and the pass of the planishing-rolls. The billet is first conducted by the rotating rollers of the inclined table of the first set of rolls to the first pass at the lower part of the same, and conducted through said pass to the rising and falling platform at the opposite side of the rolls. While this platform is raised the billet is simultaneously shifted laterally into line with the second pass of the first set, then fed through said pass onto the inclined table, and from the same through the third pass at the lower part of the first set again to the rising and falling platform. The billet is raised by the platform and simultaneously shifted into line with the fourth pass, and fed through said pass to the inclined feed-table, and from the same through the fifth pass onto the pivoted arms of the traversing carriage, which arms serve to convey the billet to a hinged platform of the carriage, and by the lifting of said platform to the upper passes of the second set of rolls. The billet is fed from said platform by means of a lifting lever-frame and a rotating feed-roller through the three upper passes of the finishing-rolls, while an inclined table at the front side of said rolls returns the billet alternately through the three lower passes of the finishing-rolls. The skelp thus formed by the action of the eleven passes is then transferred by the oscillating dogs of the carriage along an inclined plate to the guideway of the planishing-rolls and moved by feed devices to the front side of the same, where the skelp is bent up and returned through the twelfth pass of said rolls to a raised platform, and thence by another feed device to the trimming shears, it being then ready to be worked up into a tube or nails, as the case may be.

Having thus described my invention, I claim as new and desire to secure by Letters Patent—

1. The combination, with three sets of rolls arranged in line with each other and the feed devices of the same, of a traversing carriage having a hinged platform, a pivoted lever-frame for raising or lowering said platform, pivot-arms for transferring the billet from the feed devices of the first set of rolls to the hinged platform, and oscillating arms for transferring the billet to the feed devices of the third set of rolls, substantially as set forth.

2. The combination of the first set of roughing-rolls, a stationary inclined feed-table located at the front side of said rolls, said feed-table having rotating feed-rollers, and means for reversing said feed-rollers whenever required, substantially as set forth.

3. The combination, with the first set of roughing-rolls, of an inclined stationary feed-table having rotating feed-rollers, a rising and falling feed-table at the opposite side of the rolls, said feed-table having rollers at the end next to the rolls, and continuously-rotating

- feed-rollers located above the rollers of the rising and falling feed-table, substantially as set forth.
4. The combination, with the first set or roughing-rolls, of a stationary inclined feed-table having rotating feed-rollers, a rising and falling feed-table at the other side of the rolls, a shifting-frame guided in the frame of said rising and falling feed-table, and means for reciprocating the shifting-frame simultaneously with the rising and falling of the feed-table, substantially as set forth.
5. The combination, with the first set or roughing-rolls, of a stationary inclined feed-table having rotating feed-rollers, a rising and falling feed-table at the other side of the rolls, a reciprocating shifting-frame guided in the frame of said rising and falling feed-table, and an inclined adjustable guideway engaging the end of the shifting-frame, so as to regulate the extent of reciprocating motion of the shifting-frame, substantially as set forth.
6. The combination of the first set or roughing-rolls, a rising and falling feed-table at one side of the same, a reciprocating shifting device guided in the frame of said feed-table, and a traversing carriage having pivot-arms fitting in recesses of the frame of said feed-table, and a hinged platform to which the billet is transferred by the pivot-arms from the feed-table, substantially as set forth.
7. The combination of the first set or roughing-rolls, a rising and falling feed-table, a reciprocating shifting-frame, guided in the frame of the rising and falling feed-table, a traversing carriage having pivoted arms and a hinged platform, a second set of finishing-rolls, and a pivoted lever-frame for raising or lowering said platform, substantially as set forth.
8. The combination of the first set or roughing-rolls, a rising and falling feed-table at one side of the same, a reciprocating shifting device guided in the frame of said feed-table, a traversing carriage having pivoted arms fitting into recesses of the frame of the feed-table, a platform hinged to said carriage, dogs pivoted to said platform, and means for lifting said dogs above the platform, substantially as set forth.
9. The combination of the second or finishing set of rolls, a traversing carriage, a platform hinged to said carriage, a pivoted lever-frame for raising or lowering said platform, and a continuously-rotating feed-roller above the inner end of the platform, next to the rolls, substantially as set forth.
10. The combination of the second or finishing set of rolls, a stationary inclined feed-table at one side of the rolls, means for feeding the billet from said table to the rolls, a traversing carriage at the opposite side of the
- rolls, a platform hinged to said carriage, a pivoted lever-frame for raising or lowering said platform, and a continuously-rotating feed-roller above the inner end of the platform, next to the rolls, substantially as set forth.
11. The combination of the second or finishing set of rolls, a stationary inclined feed-table at the front of the same, said table having a rotary feed-roller at the outer end and guides near the inner end, an oscillating balanced roller-frame for holding the billet in contact with said feed-roller, a traversing carriage at the opposite side of the rolls, a platform hinged to said carriage, a frame for lifting or lowering said platform, and a continuously-rotating feed-roller above the inner end of the platform, by which the billet is raised and fed through the upper passes of the rolls, substantially as set forth.
12. The combination of the second or finishing set of rolls, a traversing carriage at one side of the same, a platform hinged to said carriage, balanced dogs pivoted to the carriage, a third or planishing set of rolls, an inclined plate, and means for oscillating the dogs, so as to transfer the skelp on the platform and carriage to the inclined plate and from the same by gravity to the guideway of the planishing set of rolls, substantially as set forth.
13. The combination, with the third or planishing set of rolls, of a continuously-rotating feed-roller at the rear of the same and an oscillating and balanced lever-frame having a roller, whereby the skelp is fed through below the planishing-rolls to the other side of same, substantially as set forth.
14. The combination, with the third or planishing set of rolls, of a continuously-rotating feed-roller at the rear of the same, a curved guideway at the front of the same, a balanced lever-frame having a roller for pressing the blank in contact with the feed-roller, and a raised platform at the rear of the planishing-rolls, on a level with the pass of the same, substantially as set forth.
15. The combination, with the third or planishing set of rolls, of a raised platform at the rear of the same, located on a level with the pass of the rolls, a continuously-rotating feed-roller at the opposite end of the platform, and a balanced lever-frame having a roller, said feed-roller and lever-frame feeding the skelp from the platform to the trimming-shears, substantially as set forth.

In testimony that I claim the foregoing as my invention I have signed my name in presence of two subscribing witnesses.

JOHN M. PRICE.
